UNITED STATES PATENT OFFICE.

EMMANUEL FÉLIX AUMONT, OF PARIS, FRANCE.

GAS PRODUCER AND COMPRESSOR.

1,118,095.

Specification of Letters Patent.

Patented Nov. 24, 1914.

Application filed September 18, 1912. Serial No. 721,052.

To all whom it may concern:

Be it known that I, EMMANUEL FÉLIX AUMONT, a citizen of the French Republic, residing at Paris, Department of the Seine, France, have invented certain new and useful Improvements in Gas Producers and Compressors; and I do hereby declare the following to be a full, clear, and exact description of the invention, such as will enable others skilled in the art to which it appertains to make and use the same.

This invention relates to apparatus for making a storing and dispensing medium for carbonated beverages, and has for its object the provision of an apparatus having the novel features of construction and operation, as hereinafter described.

The invention is illustrated in the accompanying drawings, in which:—

20 Figure 1 is a broken view, partly in section, of the improved apparatus showing one form of means for admitting combustion products to the injector; Figs. 2 and 3, in combination, show an apparatus in which 25 a modified form of the means for admitting the combustion products is used; and Fig. 4 is a vertical section taken on the longitudinal center line of the construction shown in Fig. 2.

30 Beverages, such as beer and the like, rapidly lose their quality when subjected to the action of air, while the preservation of such liquids is assured if they are kept under pressure by means of a medium, such as 35 carbonic acid gas. The mixture of nitrogen and carbonic acid gas formed by combustion has all the advantages of carbonic acid gas alone, besides costing very little as compared with the relative high cost of carbonic 40 acid gas.

The present apparatus is especially designed for making and storing under pressure in a simple manner, a mixture of nitrogen and carbonic acid gas to be used for 45 storing and dispensing beverages.

Referring to Fig. 1, the compressing reservoir is shown at *d* provided with an outlet *c'* controlled by a suitable valve *m*. The outlet *c'* may discharge the liquid contents of 50 the reservoir *d* wherever desired, a tank *n* being shown for this purpose into which the outlet pipe *c'* discharges. Liquid such as water is injected into the compressing reservoir *d* by a suitable injector *a* interposed in 55 the inlet *c*. As hereinbefore stated, it is de-

sirable that the storing and dispensing medium for the beverage be of such character that it will not affect the quality of the beverage. The following means is, therefore, preferably employed not only to produce 60 and furnish such medium, but to coöperate with the injector so as to automatically produce the necessary pressure in the compressing reservoir *d*. As shown in Fig. 1, this means takes the form of a burner of the 65 Bunsen type comprising the burner nozzle *t* and the burner *p* provided at its upper extremity with a burner screen *g*. Fuel is admitted to the burner through a chamber *x*, in which is located a diaphragm *u* in proximity to the lower extremity of the nozzle *t*. The diaphragm *u* so divides the chamber as to provide a lower compartment *w* in communication with the reservoir *d* by means of a conduit *v*. A by-pass *z* serves to constantly supply a small pilot-light with fuel, said pilot-light being located adjacent the burner screen *g*. A conduit *s* places the top of the burner *p* in communication with the inlet *c* of the reservoir, the communication 70 between said inlet and the conduit *s* being controlled by a check-valve *b*. A branch conduit *o*, having an inlet *o'*, is preferably provided, for the purpose hereinafter described. The operation of such construction is as follows: The liquid admitted to the reservoir *d* through the injector entrains the products of combustion produced by the burner and forces the mixture of the liquid and the burner gases into the reservoir *d*. The 75 gases separate from the liquid in the reservoir *d* and rise to the top part thereof, where they are compressed and forced through a conduit *i* into the storing tank or receptacle *k*, a check-valve *j* being provided to prevent return of the gases to the reservoir *d*. The above action takes place only when the valve *m* is open, and the pressure in the reservoir *d* thereby relieved to a certain extent. This permits the injection of the 80 liquid through the inlet *c*, the opening of the valve *b* and the admission of the gases, as hereinbefore described. There is placed in the upper portion of the reservoir *d*, a float valve *g* which closes when the liquid in 85 the reservoir reaches a predetermined level. Prior to the closing of the float valve *g*, the gases accumulating in the reservoir *d* are forced into the storing tank or receptacle *k*, as above stated. When the valve *m* is closed, 90

the injecting action continues until the pressure in the reservoir *d* is substantially equal to that of the admitted liquid, at which time the injection ceases and the valve *b* closes. 5 The pressure in the reservoir *d* then serves to lift the diaphragm *u* and cuts off the supply of fuel to the nozzle *t*, thereby extinguishing the burner. When the pressure in reservoir *d* is lowered by opening the 10 valve *m*, the diaphragm *u* lowers and the pilot-light adjacent the screen *q* ignites the burner, and the operation of the parts, as hereinbefore described, is repeated.

In the form of the apparatus shown in 15 Figs. 2 and 3, the injector *a* communicates with the lower compartment *w* of the chamber *x*, the two being separated by a diaphragm, as in the construction shown in Fig. 1. The burner and its operation are 20 similar to that shown in Fig. 1, except that above the burner is disposed a chimney *s'* having at its upper extremity, a dome-shaped closure 1 which fits the chimney *s'* loosely. The gases pass from the dome-shaped closure 1 through the passages 2 to 25 a reservoir 3. A conduit *v* provided with a coil *i* and check valve *g'* places the reservoir 3 in communication with the conduit *v*, hereinbefore described. When the valve *m* 30 is closed, the pressure in the reservoir *d* causes the liquid admitted through the conduit *c* to rise in the conduit *v*, and thereby lift the diaphragm between the chamber *x* and the compartment *w*, thus serving to cut 35 off the supply of fuel to the burner. A portion of the liquid in the conduit *v* passes through the shunt passage *i'* and serves to close the check-valve *g'*. When the valve *m* 40 is opened, the diaphragm associated with the chamber *x* and compartment *w* lowers and the pilot-light ignites the burner which produces the gases that are drawn through the chimney *s'*, closure 1, openings 2, reservoir 3 and conduit *v* to the injector *a*. The 45 reduction of pressure in the conduit *v*, resulting from the injection action at *a*, permits the combustion products to pass to the injector through the check-valve *g'*. The opening between the dome-shaped 50 closure 1 and the chimney *s'* performs the same function as the opening at *o'*, in Fig. 1, to wit, places the injector and also the burner in communication with the atmosphere, and thereby renders the operation of 55 the injector independent of the operation of the burner. That is, if the suction of the injector is very slight, the excess products of combustion will pass through this opening between the dome-shaped closure 1 and the chimney *s'*, but if the suction of the injector tends to draw in more products of combustion than supplied by the burner, air will be admitted through the opening between the dome-shaped closure 1 and the 60 chimney *s'*. The burner is designed, how- 65

ever, to furnish the products of combustion in sufficient quantities to always meet the demand of the injector, and the last-named condition will probably never occur.

Obviously numerous changes and modifications may be made in the details of construction without departing from the spirit or scope of the invention, as defined in the accompanying claims. 70

What I claim is:—

1. Apparatus of the kind described, comprising a reservoir, an injector associated therewith through which a liquid may be injected into said reservoir, a burner, means associated with said injector to admit products of combustion of said burner to the injector, and an outlet valve associated with the reservoir. 75

2. Apparatus of the kind described, comprising a reservoir, an outlet valve associated therewith, an injector to inject liquid into said reservoir, a burner, means to admit products of combustion of said burner to the injector, and a valve associated with said means through which said products of combustion pass to the injector, said last-named valve adapted to automatically close when a predetermined pressure is reached in the reservoir. 80

3. Apparatus of the kind described, comprising a reservoir, an outlet valve associated therewith, an injector to inject liquid into said reservoir, a burner, means to admit products of combustion of said burner to the injector, a valve associated with said means through which said products of combustion pass to the injector, said last-named valve adapted to automatically close when a predetermined pressure is reached in the reservoir, and means operable when the liquid in the reservoir reaches a predetermined height to effect a cessation of the flow of liquid through said injector. 95

4. An apparatus of the kind described, comprising a reservoir, an outlet valve associated therewith, an injector adapted to inject a liquid into said reservoir, a burner, means to admit products of combustion of said burner to said injector, and means controlled by the pressure in said reservoir to control the supply of fuel to said burner. 110

5. Apparatus of the kind described, comprising a reservoir, an injector associated therewith through which a liquid may be injected into said reservoir, a burner, means associated with said injector to admit products of combustion of said burner to the injector, an outlet valve associated with the reservoir, and means to collect the gases accumulated in said reservoir. 120

6. Apparatus of the kind described, comprising a reservoir, an injector associated therewith through which a liquid may be injected into the reservoir, a burner, means to conduct the products of combustion of 130

said burner to the injector, said means being in communication with the atmosphere, for the purpose described.

7. Apparatus of the kind described, comprising a reservoir, an injector associated therewith through which a liquid may be injected into the reservoir, a burner, means to admit products of combustion of said burner to the injector, a diaphragm chamber associated with the burner and in communication with said reservoir, a diaphragm

in said chamber subjected to the pressure in said reservoir, and means whereby the movement of the diaphragm by the change of pressure in the reservoir varies the supply 15 of fuel to the burner.

In testimony whereof I affix my signature, in presence of two witnesses.

EMMANUEL FÉLIX AUMONT.
